UNITED STATES PATENT OFFICE.

HERMAN H. WOLTER, OF MERIDEN, CONNECTICUT, ASSIGNOR TO THE MILLER COMPANY, OF NEW YORK, N. Y., A CORPORATION OF CONNECTICUT.

DESIGN FOR A LIGHTING-FIXTURE PLATE.

Application filed March 5, 1924. Serial No. 8,835. Term of patent $3\frac{1}{2}$ years.

To all whom it may concern:

Be it known that I, HERMAN H. WOLTER, a citizen of the United States, residing in Meriden, in the county of New Haven and State of Connecticut, have invented a new, original, and ornamental Design for Lighting-Fixture Plate, of which the following is a specification, reference being had to the accompanying drawing, forming a part thereof.

Fig. 1 is a perspective view of the lighting fixture plate made according to my design.

Fig. 2 is a side view of the plate shown in Fig. 1 for the purpose of disclosing the contour and having the ornamentation omitted.

I claim:

The ornamental design for a lighting fixture plate, as shown.

HERMAN H. WOLTER.
